UNITED STATES PATENT OFFICE.

GEORGE W. STITT AND ORVIS D. BLOOM, OF PORTLAND, OREGON.

TAG-FASTENER.

1,288,265.

Specification of Letters Patent. Patented Dec. 17, 1918.

Application filed April 29, 1916. Serial No. 94,292.

To all whom it may concern:

Be it known that we, GEORGE W. STITT and ORVIS D. BLOOM, both citizens of the United States, and both residing in Portland, in the 5 county of Multnomah and State of Oregon, have invented certain new and useful Improvements in Tag-Fasteners; and we do hereby declare that the following is a full, clear, and exact description of the invention, 10 which will enable others skilled in the art to which it appertains to make and use the same, reference being had to the accompanying drawings, and to the characters of reference marked thereon, which form a 15 part of this specification.

Our improvement relates to improvements in tag fasteners, the features of which will be fully hereinafter described and claimed.

The object of our invention is to obtain a 20 tag-fastener constructed of spring wire and of such construction that it will attach a tag made of paper, metal or other material, to articles of merchandise, sacks, bales, cloth, rolls of carpet, bundles of wire, iron in small 25 form, pieces of machinery and in fact any article or material that one of the three forms will and can be attached to.

The further object of our invention is the 30 rapidity, and speed with which tags can be attached to articles of merchandise, etc., therefore the name instantaneous tag-fastener.

It is further our object to so arrange the 35 form in which the fastener is shaped, that three different shapes are constructed of the one general design.

In the accompanying drawings our tag-fastener is shown in its three different shapes, the **8** and **0** shape are shown both 40 open and closed, also detail of points and edge or right-angle view.

Similar letters of reference refer to corresponding parts in all the figures, in which—

45 Figure 1 shows a side view of the tag-fastener in a **U**-shape and having a central loop **b**, of sufficient size to hold the desired tag. The fastener is formed of a single piece of spring wire and comprises the central loop 50 or bend **b**, the arms **d** and **e**, which in this figure or shape are straight, the return bends **f** **f**, forming the inserting points and following back along the inner side of **d** and **e** to a distance indicated by **x**, where they 55 leave abruptly, forming the two spurs **c** **c**.

Fig. 2 shows a side view of the tag-fas-

tener in an **8** shape, and in a normal or closed position. Material and general description much the same as Fig. 1. The central arc **b**, the sides **d** and **e**, the return bends forming the points at **f** **f**, and the spurs **c** and **c**, but instead of being straight the sides or or arms **d** and **e** are bent in the form of a reverse curve so as to cross each other at **y**.

Fig. 3 shows a side view of the tag-fas- 65 tener in an **0** shape. Material and general description much the same as Fig. 1. The central arc or loop **b**, the sides **d** and **e**, the return bends or points **f** and **f**, and the spurs **c** and **c**, but instead of being straight 70 the sides or arms **d** and **e** are bent outward, and these sides, in connection with the arc **b**, and ends **a** form a complete circle.

Fig. 4 is an edge view or a view at right angles to and of Fig. 1, showing a com- 75 mon shipping-tag attached.

In Fig. 5 pressure has been brought to bear on the arms **d** and **e**, at the position indicated by **z** **z**, which readily separate the ends at **a**, thus showing the shape design- 80 nated as Fig. 2 open, and ready for action.

Fig. 6 shows the shape designated as Fig. 3 open and ready to embrace material to be tagged.

Fig. 7 is a detail of the points and spurs, 85 which are the inserting and holding feature, and are the same in Fig. 1, Fig. 2 and Fig. 3.

In use, one of the ends at **a**, the point **f** and spur **c**, is passed through the eyelet 90 until the tag rests at **b**. If the **U** shape Fig. 1 is used, one thrust of the ends **a** through the material to be tagged is all that is required. Sacked materials, rope, burlap covered materials or merchandise, etc., 95 can in this manner be tagged instantly and with one hand, the spurs **c** **c** retaining the tag in a fastened position. For any use that would not allow of the thrusting motion of fastening, Fig. 2 and Fig. 3, with 100 the same ends **a**, points **f** **f**, and spurs **c** **c**, but bent arms **d** and **e**, can be satisfactorily used, thus for wire, nursery stock, materials which will not admit of the points going straight through, etc.

105 Among the many advantages of our improved tag-fastener may be here mentioned that it can be so easily attached and with great rapidity to almost any material and of almost any shape and form of material, 110 that it is a more universal tag-fastener, being adapted to commercial or shipping-tags,

price-tags and information tags, and fastening securely and instantly.

We are aware that prior to our invention there have been tag-fasteners invented and manufactured, but—

What we claim, is—

As an improved article of manufacture, the tag-fastener having direct inserting points, as herewith described, consisting of 10 a single piece of wire, at a sufficient distance from the ends of the wire of the fastener, the said wire being bent abruptly back against itself, pressed firmly together and the extreme ends of the said bends pointed,

to form the inserting points, the wire continuing back against and along itself for a distance sufficient in length, at which point the free ends of the wire are turned away from and at an acute angle to the wire proper to form retaining spurs or barbs and 20 will retain a hold on or in the material substantially as the three forms herein set forth.

GEO. W. STITT.
ORVIS D. BLOOM.
